UNITED STATES PATENT OFFICE.

ALBERT GOTTSCHALK, OF NEW YORK, N. Y., ASSIGNOR TO NATIONAL PNEUMATIC COMPANY, OF NEW YORK, N. Y., A CORPORATION OF WEST VIRGINIA.

DOOR-OPERATING MOTOR.

Application filed September 13, 1919. Serial No. 323,656.

This invention relates to door operating motors, and particularly to motors of the pneumatic type.

A further object of the invention is to provide a door operating motor which is simple in structure, efficient in operation and economical of manufacture.

A further object of the invention is to provide a door operating motor of the character described wherein the control of the operation thereof is simple and efficiently effected.

A further object of the invention is to provide means controlled by the closing movement of the door to automatically and mechanically shut off the supply of fluid pressure for causing the door closing movement as distinguished from methods heretofore known in art which consists of pneumatically operated means for accomplishing this purpose.

Further objects of the invention will appear more fully hereinafter.

The invention consists substantially in the construction, combination, location and relative arrangement of parts all as will be more fully hereinafter set forth as shown in the accompanying drawings and finally pointed out in the appended claims.

Referring to the drawings:—

Fig. 1 is a view in vertical longitudinal section of a door operating motor embodying the principles of my invention.

Fig. 2 is an end view of the same.

Fig. 3 is an enlarged sectional view of the valve end of the motor embodying my invention.

Fig. 4 is a view in side elevation, partially in section, of a combined cylinder head and valve seat embodying my invention.

Fig. 5 is a face view of the same.

Fig. 6 is a rear view of the same.

Fig. 7 is a view in side elevation, partially in section, taken on the line 7, 7, Fig. 9, of a valve employed in accordance therewith.

Fig. 8 is a face view of the same.

Fig. 9 is a rear view of the same.

Fig. 10 is a view similar to Fig. 1 showing a slightly modified form of my invention.

Fig. 11 is a view in end elevation of the

valve control mechanism shown in Fig. 10.

Fig. 12 is a sectional view taken on the line 12, 12, Fig. 10, looking in the direction 55 of the arrows.

The same part is designated by the same reference character wherever it occurs throughout the several views.

It is among the special purposes of my present invention to provide a door operating motor of the pneumatic type, and especially of the type that is known in the art as the differential motor, comprising in essence cylinders 1 and 2 of different diameters in 65 which operate respectively pistons 3 and 4, which pistons are connected together by means of rack bar 5, which meshes with the gear segment 6 mounted on shaft 7, to which is secured rod 8, the end of which is connected to the door, so that upon movement of the pistons 3 and 4 in one direction or the other the door movements are controlled. It is common in motors of this nature to maintain a constant supply of fluid pressure behind the piston of smaller diameter. In this instance fluid pressure is supplied through pipe line 9 and through passage 10 into the cylinder behind the piston 4. With this arrangement, and when cylinder 1 is open to 70 exhaust, fluid pressure behind piston 4 causes the pistons and piston rod to move toward the left from the position illustrated in Fig. 1 so that the door assumes its open position.

When it is desired to close the door, fluid pressure is admitted behind the piston 3 in cylinder 1 so that the pressure being equal on the respective pistons, but one being larger than the other, the pistons and piston rod are caused to move toward the right 75 into position shown by Fig. 1. Many various controlling valves and mechanism, some consisting of differential piston motors themselves, have been devised for controlling the operation of the motor, but the simplicity of my present invention, together with its efficiency, is believed to be far superior to any such devices.

In accordance with my present invention I employ a combined valve seat and cylinder head, and in the form illustrated in Fig. 1, I locate the same over the end of the cylinder of smaller diameter, namely, cylinder 2. The details of the valve construction are

shown in Figs. 3 to 9 inclusive. The valve consists of a spindle 20 threaded at its end as at 21 and provided with a circular valve member 22 at its inner end. The valve member 22 has passages therein as at 23 for establishing communication between the respective passages hereinafter to be described. The cylinder wall of the motor is provided with a passage 24 extending throughout the length of the motor and into the cylinder 1 through its head 25, as clearly shown in Fig. 1. The valve seat and cylinder head shown in Figs. 4, 5 and 6 comprise the valve seat portion 27, the cylinder head portion 28, provided with a passage 29 at one portion thereof in the shape of a U to establish connection between passage 24 and the valve. It also has a passage 30 to establish connection between valve and exhaust. 20 The stem 20 of the valve extends through the orifice 31 in the combined cylinder head and valve seat. I also provide a lever 20' held in place by a nut 32 screwing over the threads 21 of the valve stem, and between 25 the lever and the head is interposed a spring 34 to normally maintain the valve in its proper seating position relative to its valve seat. The valve in addition to the passage 23 has a port 33 extending completely 30 through the same, which port is adapted in one position of the valve to establish communication between the cylinder 2 and the passage 29, to thereby enable fluid pressure to get behind the cylinder of larger diameter to close the door. Any suitable means 35 may be employed for operating the valve, for example, a handle 40 may be secured to the valve stem and rotated in an obvious manner to control the valve movements. 40 From the foregoing it will be seen that when the valve is rotated by means of handle 40 so that fluid pressure is admitted into the cylinder of larger diameter behind the piston 3 the parts will assume the position 45 shown in Fig. 1, that is, with the door motor in its door closed position. When it is desired to open the door the valve spindle 20 is turned by means of the handle 40, as illustrated, so that the passage 23 in the valve will establish connection between the passages 24 and 29 and the exhaust passage 30.

Many modifications will readily occur to those skilled in the art without departing 50 from the spirit and scope of my invention, for example, to secure a cushioning effect of the motor at the limit of its movement the passage 24 may communicate with the cylinder 1 through restricted port so that 55 a cushioning effect is secured upon the opening movement of the door. Likewise, inasmuch as fluid pressure is constantly behind the piston 4 through pipe line 9, passage 10, the closing movement of the door is cushioned against fluid pressure. A further 60

change is shown in Fig. 10 wherein I locate the combined valve seat and cylinder head at the end of the cylinder of larger diameter. In this arrangement the valve generally illustrated at 60 controls the supply 70 of fluid pressure to both cylinders and the exhaust thereof from the cylinder of larger diameter 1. Fluid pressure is supplied from the pipe line 9 to passage 61 in the valve seat and through passage 62 in valve to passage 75 63 in the valve seat to passage 65 in the cylinder casting, terminating in port 66 into the cylinder 2 of smaller diameter. At the same time passage 67 in the valve establishes communication between passage 68 80 terminating in passage 69 in the valve seat and the exhaust 70 in the valve seat. In this arrangement I prefer to have the door motor at the limit of its movement as illustrated in Fig. 1 when the door has reached 85 its closed position, and in accordance with my invention, I propose to mount the handle 71, which controls the valve 60 in alignment with the door operating arm 8 so that when the door has reached the limit of its movement in its closed position the arm or handle 71 controlling the valve 60 will have been rotated a sufficient distance to shut off the source of fluid pressure and thereby prevent waste thereof. 95

With the foregoing arrangement, that is, with the valve in the cylinder of larger diameter, and in its lap position as shown in Fig. 12, the air contained in both cylinders is trapped. While it is desirous to prevent 100 leakage from the cylinders if possible, there is always apt to be leakage after use of the motor due to the wear of the parts, and it is apparent that leakage of the trapped air in the cylinder of larger diameter alone, 105 would cause a partial opening of the door. To prevent this I make use of an equalizing port 63 in the valve to establish free communication between the cylinders 1 and 2 to thereby prevent a partial opening of the door due to the leakage of the trapped air from the cylinder of larger diameter alone. 110

Having now set forth the objects and nature of my invention, and having shown and described structures embodying the principles thereof, what I claim as new and useful, and of my own invention, and desire to secure by Letters Patent, is,—

1. In a fluid pressure actuated motor, the combination with differential cylinders having a passage connecting them, pistons operating therein, a rotative valve operating within the cylinder of smaller diameter, said valve controlling said passage to control the supply of fluid pressure to and the exhaust thereof from the cylinder of larger diameter, and means for maintaining a supply of fluid pressure behind the piston in the cylinder of smaller diameter. 125

2. In a fluid pressure actuated motor, the 130

combination with differential cylinders having a passage connecting them, pistons operating therein, heads for said cylinders, a valve seat on the head of and located within the cylinder of smaller diameter, a valve operating on said seat and controlling said passage to control the supply of fluid pressure to and the exhaust thereof from the

cylinder of larger diameter, and means for maintaining a supply of fluid pressure to the cylinder of smaller diameter.

In testimony whereof I have hereunto set my hand on this 5th day of September A. D., 1919.

ALBERT GOTTSCHALK.
